UNITED STATES PATENT OFFICE.

GEORGE ELMER KRAEER, OF WILSON, OKLAHOMA, ASSIGNOR OF ONE-SIXTH TO LE ROY JOHNSTON AND ONE-SIXTH TO EDWARD TURNER SHOLTUS, BOTH OF WILSON, OKLAHOMA, AND ONE-SIXTH TO WILLIAM OLIVER CLAY, OF WIRT, OKLAHOMA.

UNDERREAMER DRESSING BLOCK.

Application filed October 24, 1924. Serial No. 745,724.

To all whom it may concern:

Be it known that I, GEORGE E. KRAEER, a citizen of the United States, and a resident of Wilson, in the county of Carter and State of Oklahoma, have invented a new and Improved Underreamer Dressing Block, of which the following is a full, clear, and exact description.

This invention relates to underreamer dressing blocks and is more particularly designed for the purpose of holding a well known type of underreamer cutter in a perfectly upright rigid position so that the cutter can be dressed by the operator without damage to the original form or alignment of the cutter.

An object of the invention is to provide a block of the character stated, comprising two members carrying forms which fit the back and front sides of the cutter so that when the members of the block are moved toward each other and clamped the cutter will be securely and properly held.

A further object is to provide a block of this character which can be quickly adjusted to clamping or releasing position, which will be strong and durable in use, and which will most efficiently perform the functions for which it is intended.

With these and other objects in view, the invention consists in certain novel features of construction and combinations and arrangements of parts which will be more fully hereinafter described and pointed out in the claims.

In the accompanying drawings—

Fig. 1 is a perspective view of one of the block members;

Fig. 2 is a perspective view of the other block member;

Fig. 3 is a view in vertical section through the center of the device when in operative position, the cutter being illustrated by dot and dash lines;

Fig. 4 is a view in horizontal section on the line 4-4 of Fig. 3; and

Fig. 5 is a perspective view illustrating the cam lever and its mount.

My improved block comprises two members 1 and 2, which are of suitable material to give the desired strength and durability. Member 1 is provided at its lower portion with a platform 3 having parallel webs 6 thereon, and the member 1 is adapted to

slide on the platform 3 and is formed in its lower face with grooves 7 to receive the webs 6 and prevent the possibility of lateral displacement.

The blocks 1 and 2 in their inner adjacent faces are recessed, as shown at 8, the walls of these recesses tapering longitudinally so that the recesses are widest at their upper ends and narrowest at their lower ends.

In these tapering recesses I locate forms 9. These forms are so shaped that when together they form clamping recesses conforming in exact shape to a portion of the cutter to be dressed so that while they clamp the cutter securely they do not alter the shape nor injure the same in any manner. It is, of course, to be understood that these forms 9 may be removed and replaced by other forms in accordance with the shape of the cutter to be dressed or in accordance with various sizes of said cutters, and hence the forms are made removable and are securely held by reason of their shape, which corresponds in shape to the walls of the recesses or grooves in which they are housed in the block members.

The block members 1 and 2 are provided with aligned openings 10 receiving bolts 11. These bolts 11 are preferably screw-threaded at one end, as shown at 12, and are provided with nuts 13 to permit a certain amount of adjustment of the bolts longitudinally to insure a proper functioning of the device.

The openings 10 are enlarged transversely adjacent the inner faces of the block members to provide housing for coil springs 14 and also to provide shoulders 15 in the respective block members against which the ends of the spring bear and tend to press the block members apart.

The bolts 11 at one end are formed with eyes 16 constituting bearings for an eccentric or crank shaft 17, said shaft having a handle or crank arm 18 at one end to facilitate the turning of the shaft. The eccentric or cam portion 19 of the shaft 17 is formed by offsetting the shaft between the bearings 16 so that when the shaft is given a turn or partial turn in the proper direction this cam will engage the back of the member 1 and force it toward the member 2 to securely clamp the cutter. By moving

the eccentric slightly past the longitudinal center of the shaft the parts will be securely held against accidental displacement.

Handles 20 are secured to the member 2 at respective sides thereof so as to facilitate the manual movement of the block as a whole, and these handles are properly shaped so as not to interfere with any of the operations or movements of parts above explained.

The operation is as follows:

Assuming the blocks 9 to be in position in the members 1 and 2 and the member 1 located on the platform 3, the cutter, indicated by dot and dash lines in Figure 3, is inserted in position and the lever 18 is moved to turn shaft 17 and by reason of the cam or eccentric 19 forces the members toward each other to securely clamp the cutter. When the cutter is to be released, the shaft is turned in the opposite direction and the springs 14 will force the members 1 and 2 apart sufficiently to make a free removal of the cutter.

Various slight changes and alterations might be made in the general form of the parts described without departing from my

invention, and hence I do not limit myself to the precise details set forth but consider myself at liberty to make such slight changes and alterations as fairly fall within the spirit and scope of the appended claims.

I claim:

1. A block of the character described, comprising two members, each member having tapering recesses in its inner face, removable forms located in said recesses and having tapering walls corresponding with the taper thereof, bolts connecting the members, and means for moving one of said members toward and away from the other member.

2. A block of the character described, comprising two members, each member having tapering recesses in its inner face, removable forms located in said recesses and having tapering walls corresponding with the taper thereof, bolts connecting the members, means for moving one of said members toward and away from the other member, one of said members constituting a support for the other member, and handles on said supporting member.

GEORGE ELMER KRAEER.
